Attorney.

UNITED STATES PATENT OFFICE.

JOHN F. HOLLIDAY, OF WASHINGTON, INDIANA, ASSIGNOR TO HINCHER MANUFACTURING COMPANY, OF WASHINGTON, INDIANA, A CORPORATION OF INDIANA.

FOLDING STEPLADDER STOOL.

1,427,293.

Specification of Letters Patent. Patented Aug. 29, 1922.

Application filed June 1, 1921. Serial No. 474,145.

To all whom it may concern:

Be it known that I, JOHN F. HOLLIDAY, a citizen of the United States, residing at Washington, in the county of Daviess and 5 the State of Indiana, have invented new and useful Improvements in Folding Stepladder Stools, of which the following is a specification.

This invention relates to a combined step-ladder and stool for household use, which 10 may be folded into a compact body for carrying from place to place without striking against other furniture, and for convenient storage when not in use.

15 Folding step-ladder stools of this character are now in use, many of which are dangerous owing to their disposition to tip and throw the person using them when the weight of the user is applied near the front 20 of the top board of the combined stool and stepladder. In the use of such ladders for hanging pictures, curtains and the like requiring frequently a long reach in an upward direction, the persons using them very 25 frequently stand upon their toes to increase their reach, thereby delivering their weight upon the front edge of the board beyond the adjacent hinge line, causing the board to tilt forward and frequently resulting in seri- 30 ous injury to the user.

One of the principal objects of this invention is to place the hinge or fulcrum of the top board so near the front edge of the ladder as to make the tilting of the board 35 impossible when the user stands on his toes under the conditions mentioned above.

A further object is to simplify the construction without in any manner lessening the strength and safety of the device, and 40 also to deliver the weight, as of a person standing on the stool seat or top board of the ladder, against the end of the grain of four supporting legs thereby avoiding any tendency to split the legs; also, to provide bat- 45 tens to reinforce the top board and also to provide the proper bearing surfaces for said leg-ends.

A still further object of the invention is 50 to provide hinges of special construction and application, and to retain them in place by means of rivets that will also reinforce the leg-ends where the hinges are secured to the legs and side-pieces, and which will substantially rivet the battens to the top board.

55 I accomplish the above, and other objects

which will hereinafter appear, by the mechanism illustrated in the accompanying drawing, in which:—

Fig. 1 is a perspective view of the invention in open position for use as a stool or 60 ladder. Fig. 2 is a side view of the same in its closed or folded condition. Fig. 3 is an under side view of the top board with the legs folded, said legs being broken away and removed for the most part. Fig. 4 is a view 65 in side elevation of the upper portion of the invention in open condition, and Fig. 5 is a plan view of my special hinge.

Like characters of reference indicate like parts in the several views of the drawing. 70

The top board or seat member 6 is of wood with the grain running transversely from right to left of the device as a whole. It is strengthened and kept from splitting with the grain by a pair of battens 7, 7, 75 which are placed near the ends of the board crosswise of the grain as shown in Fig. 3. Those ends of the battens which are at the step section side of the device are provided with bevels 8, at the proper angle to suitably slope the two side pieces 9, 9, of the ladder when the squared ends of said pieces are against their respective bevels. The battens are considerably wider than the thickness of the side pieces of the ladder for 85 the greater distribution of the load to the board 6, and also to afford a wider bearing for the leaves 10 of the hinges by which the side pieces 9, 9, of the ladder are connected and likewise by which a pair of legs 12, 12, 90 are attached to said battens. The leaves 11, 11, of the hinges are of the same width as the thickness of members 9, 9, and 12, 12, which to avoid clumsiness in appearance are preferably thinner than the width of the 95 hinge leaves 10. The leaves 10 of said hinges are made of additional width as shown here and described (see Fig. 5) in order to afford wider bearings where the hinges attach, to prevent unsteady side 100 movement and vibration, as when a person is standing on the ladder and reaching far to either side.

It will be noted that the leaves 10 of the hinges, by which the legs 12 are attached, 105 are turned inwardly of the stool and from the hinge pin, and will be contacted by the end of the corresponding leg in the open position of the device (see Figs. 1 and 4). The other leaf 11 is against the outer edge 110

of the leg. As shown in Fig. 4 the hinge pins of the two leg hinges are at the adjacent end of the battens 7, 7, very close to the rear edge of the top board of the ladder, 5 so that a person standing on tip toes on board 6 will deliver his weight directly above the fulcrum or to the front thereof and there will be no tendency for the board to tilt and cause an accident. The leaves 10 of the hinges securing the side-pieces 9 are assembled as shown in Fig. 4 of the drawing. Each leaf 11 of the hinges is secured to its side piece 9 or leg 12 by means of a rivet 13, which extends through the leaf and 15 also through the side piece or leg. The leaf here serves as a bearing plate on one side of the wooden member, and the latter is securely held between said plate and the head of the rivet, which may be reinforced 20 with a washer as shown in Fig 3, and thus the wooden member is bound in a manner to keep it from splitting with the grain at the end. The opposite hinge leaves 10 of the side pieces 9 and legs 12 are each secured 25 to their respective batten 7 by a rivet 13 which extends through the leaf, batten, and top board, the leaf here also acting as a bearing plate for the rivet and all of the members through which the rivet passes 30 being permanently and securely united. In addition to a rivet fastening each hinge leaf there is a screw 15 through the leaf into the wooden member to prevent side-play between the leaf and wooden member. It will 35 thus be noted that both leaves of the four hinges are permanently and rigidly fastened to their respective wooden members thereby adding greatly to the safety of the ladder.

Suitable steps 16, 16, connect the side 40 pieces 9, 9, by which the steps are supported, and the legs 12, 12, are connected and braced by the horizontal bars 17 as shown in Fig. 1.

A pair of metal bars 18, 18, have an end 45 of each pivotally connected with the respective side pieces 9, 9, and have their other ends similarly connected with the respective legs 12, 12. These bars assume the position shown in Fig. 1, when the device is open 50 for use, and the position shown in Fig. 2 when it is folded. The bars 18, 18, will preferably be bent as shown to cause them to fold more neatly.

A large kerf 19 is made for a hand-hold 55 on the under side of the board 6.

The article as above described is extremely portable and durable. Any weight on the top board is well distributed to the two legs and to the two side pieces of the ladder without any danger of accidentally tilting the top board and collapsing the device by an abnormal application of the load, and the load is delivered against the end of the grain of the legs and side pieces, thereby avoiding any tendency to split them. An inspection 60 of Fig. 4 will show that the two leaves of the hinges connecting legs 12 with their battens are folded back towards each other abnormally as compared with the usual hinge, and a special hinge cut away at the 65 joint to permit this is required. The leaf is cut away just far enough so the remaining metal will act as a stop to keep the hinge from opening back further and loosening the 70 screws.

While I have here shown and described the best form of my invention now known to me, it is evident that many changes in minor details are possible without departing from the spirit of the invention, and I therefore 80 do not desire to be limited any more than is required by the state of the art and as made necessary by the appended claim.

I claim:—

In a combined folding stool and step ladder, comprising a top board and step section, under-side battens crossing the grain of the board and beveled at their ends next to the step-section, said step-section comprising side-pieces having their upper ends substantially at right angles to the longitudinal grain of said pieces and bearing against the bevels of the respective battens when the device is in use as a stool and ladder, a pair of legs having their upper ends substantially at right angles to the longitudinal grain of the legs, leaf hinges connecting the side pieces and legs with the respective battens, a leaf of each leg hinge being between the end of the leg and batten when the device 90 is in operative position with the joint of the hinge at the end of the batten and approximately under the rear edge of the top board, steps connecting said side-pieces, and braces pivotally connecting the side-pieces 95 and legs.

Signed at Indianapolis, Indiana, this the 4th day of May, 1921.

JOHN F. HOLLIDAY.
